UNITED STATES PATENT OFFICE.

ALBERT J. GATES AND THOMAS W. CAPEN, OF CHICAGO, ILLINOIS, ASSIGNEES TO THE GATES IRON WORKS, OF SAME PLACE.

DESIGN FOR AN ORE-CRUSHER FRAME.

SPECIFICATION forming part of Design No. 32,903, dated July 3, 1900.

Application filed May 28, 1900. Serial No. 18,328. Term of patent 14 years.

To all whom it may concern:

Be it known that we, ALBERT J. GATES and THOMAS W. CAPEN, citizens of the United States, residing at Chicago, in the county of Cook and State of Illinois, have invented and produced a new and original Design for Ore-Crusher Frames, of which the following is a specification, reference being had to the accompanying drawing, forming a part hereof.

In the accompanying drawing the figure represents a perspective view of the ore-crusher frame as constructed in accordance with our design.

As shown in the drawing, the leading or material feature of our design consists in the hub portion A, provided with three outwardly

and downwardly extending arms B, each ending in a T-shaped foot or lug portion C.

Having described our invention, what we claim as new, and desire to secure by Letters ²⁰ Patent, is—

The design for an ore-crusher frame, as herein shown and described.

In testimony whereof we have hereunto signed our names to this specification in the ²⁵ presence of two subscribing witnesses.

ALBERT J. GATES.
THOMAS W. CAPEN.
